(57) **CLAIM**

The ornamental design for the component part of a container assembly, as shown and described.

DESCRIPTION

FIG. 1 is a top plan view of a container assembly in which the component part embodying our design resides;

FIG. 2 is a side elevation view of the container assembly of FIG. 1, the other three sides being identical;

FIG. 3 is a bottom view of the container assembly of FIG. 1;

FIG. 4 is a exploded perspective view from above of the container assembly showing the component part embodying our design intermediate the top and bottom portions of the container assembly of FIGS. 1-3; and,

FIG. 5 is a exploded perspective view from below showing the component parts embodying our design intermediate the top and bottom portions of the container assembly of FIGS. 1-3. The container assembly parts shown in broken lines set forth the environment of the component part and form no part of the design to be patented.
